PLURAL TEMPERATURE REFRIGERATION SYSTEM

Malcolm G. Shoemaker, Doylestown, Pa., assignor
to Philco Corporation, Philadelphia, Pa., a corporation of Pennsylvania

Application February 7, 1952, Serial No. 270,325

3 Claims. (Cl. 62—8)

1

The invention hereinafter disclosed and claimed relates to refrigeration, being concerned with refrigeration systems having provision for rapid and automatic removal of frost from the evaporator means, and which systems also contemplate "modulating," or controlling, the refrigerating temperature of the evaporator means. More particularly, my invention has to do with improvements in plural compartment refrigerators of the type which not only include a main storage compartment normally maintained at temperatures above the freezing point of water, but also a compartment maintained at relatively low sharp-freezing temperatures suitable for the preservation of foods over extended periods of time.

With still more particularity, the invention relates to refrigeration systems of the type which include two series-connected evaporators normally operable to maintain a pair of compartments at different predetermined temperature conditions.

Broadly, it is the primary object of the invention to provide for heating of one of the evaporators, in order to defrost the same, while continuing the normal refrigerating function of the other evaporator.

In one aspect of the invention it is an object to provide defrosting and modulating apparatus controlled by circuits which are of simple and inexpensive type by virtue of having certain control elements in common.

Among the more significant advantages of the apparatus of the invention is the high thermodynamic efficiency thereof, this advantage being achieved, in the manner fully set forth in what follows, by virtue of the fact that refrigerant condensed in one evaporator, in order to defrost the same, is re-evaporated in the other evaporator, thereby being immediately useful to provide refrigeration in said other evaporator.

The apparatus is also advantageous in that it utilizes simple control elements of known and proved type. In this connection the various control functions are preferably carried out through the agency of simple solenoid-operated valves so employed in the system that leakage at the valves, as long as it is not excessive, does not seriously impair the operability of the equipment.

Additionally the apparatus is considerably less expensive than other known types of defrosting equipment, and particularly is this the case as compared with devices of the type which utilize resistance heating elements arranged in heat exchange relation with the evaporator.

2

In the achievement of the above-stated general objectives I provide, in a refrigeration system including a pair of series-connected evaporators, a pair of restrictors one of which is disposed between the condensing means and the evaporator which is to be defrosted and the other of which is disposed between the two evaporators. There is further included apparatus providing, selectively, either for condensation of gaseous refrigerant within one of the evaporators and consequent heating of the same for defrosting purposes, or for modulation of the refrigerating temperature of that evaporator, the stated apparatus taking the form of a pair of conduits each arranged to by-pass an associated one of said restrictors, together with control means effective, when condensation of gaseous refrigerant is desired, to cause refrigerant to flow through one of said conduits by-passing only the restrictor which is associated with the evaporator to be defrosted. The control means further serves, when modulation of the refrigerating temperature of the latter evaporator is desired, to cause flow of refrigerant through the other of said conduits by-passing only the other restrictor. The concepts of the invention are applicable, generally, to refrigeration machines in which it is desired to defrost one of a pair of series-connected evaporators without interfering with the operation of the other, or to modulate the refrigerating temperature of one only of the evaporators.

The manner in which the foregoing objects and advantages may best be achieved will be understood from a consideration of the following specification considered in conjunction with the accompanying drawing, the single figure of which comprises a diagrammatic representation of a preferred embodiment of my invention.

Now making more detailed reference to the drawing, it will be seen that the illustrated embodiment of the invention includes elements common to refrigeration systems of conventional type, these elements comprising a compressor 10, a condenser 11, a pair of series-connected evaporators 12 and 13, each of which is arranged in heat exchange relation with a compartment or zone to be cooled, the evaporator 12 being adapted to cool the compartment shown diagrammatically at 14, and the evaporator 13 being arranged to refrigerate the compartment 15. A pair of restrictors 16 and 17, which preferably are of the capillary tube type provide for flow of refrigerant from the condenser 11, and expansion of the same in the evaporators 12 and 13, the resultant warm gaseous refrigerant being re-

turned to the condenser 10 through a suction line shown at 18. The normal operation of the system, as thus far described, is well known and requires no detailed description herein.

In particular accordance with the present invention, however, the apparatus further includes a pair of conduits 19 and 20 each of which is adapted, under certain conditions of operation, to by-pass an associated one of the restrictors 16 and 17. Thus the conduit 19 is arranged to 10 by-pass the restrictor 16 and the conduit 20 is similarly arranged as respects the restrictor 17.

Means is provided to control the flow of refrigerant through the by-pass conduits and, for the purposes of this disclosure, this means takes the form of a pair of solenoid-actuated valves of known type, shown diagrammatically at 21 and 22, the valve 21 controlling flow of refrigerant through the conduit 19 and the valve 22 controlling flow through the conduit 20.

The apparatus further includes three pressure-responsive temperature control devices which are preferably of the known Sylphon bellows type, these temperature control devices being shown at 23, 24 and 25. As will be more fully understood from what follows, the device 23, which is provided with a control bulb 23a, is responsive to the temperature of the evaporator 13 which refrigerates compartment 15, this compartment preferably comprising a low temperature compartment adapted for the storage of frozen foods. When normal refrigeration is required the compressor 10 is placed across the line L through conductors 26 and 27, under the control of a switch 28 associated with the device 23.

A main switch of the double-throw, double-pole type is shown at 29, this switch serving to control the defrosting operation and including a pair of switch blades or arms 30 and 31 cooperable with associated contacts which appear in the drawing. It is to be understood that this switch is moved between left and right-hand terminal positions, to initiate and to terminate the defrosting cycle, such movement of the switch being under the control of any suitable actuator (shown diagrammatically at 32), such for example as any one of a number of known timing devices. Alternatively the switch may be controlled manually.

It is contemplated that the valves 21 and 22 be of the normally closed type, that is, of the type which remains closed in the absence of supply of electrical current thereto. The operation of the equipment during defrosting is as follows:

Upon movement of the main switch 29 to the left-hand (dotted line) position as viewed in the drawing, valve 21 is placed across the line through the contacts of a switch 33 (this switch is associated with control device 25 and, as later described, is responsive to the temperature of the evaporator 12 to terminate the defrosting operation should it not first be terminated through movement of the main switch 32), through the right and left-hand blades 30 and 31 of the main switch, which then occupies the left-hand position shown in dotted lines, and thence through a conductor 34 and the aforesaid conductor 27. Energization of the solenoid associated with valve 21 results in opening the valve and consequent flow of refrigerant through the conduit 19, bypassing the restrictor 16.

It is to be noted that this operation takes place independently of the control normally imposed by the device 23, since the switch contacts

of that device are shunted through the blades of the main switch and the conductor 34. It will also be observed that when defrosting is initiated in the manner above described, the compressor is energized, regardless of the position of the switch 28, since the compressor is also placed across the line through conductors 26 and 27 and through the left-hand blade of the main switch 29. Valve 22, which is under the control of pressure-responsive switch device 24 (through the right-hand blade of the main switch 29) remains unenergized, and therefore closed, during the defrosting operation.

Immediately upon opening of the valve 21 gaseous refrigerant flows through the conduit 19 and is delivered directly to the cool, frost-laden evaporator 12 wherein it is condensed. Such condensation results in a transfer of latent heat which warms the evaporator and defrosts the same, as will be understood without further description. It is particularly to be noted, however, that in accordance with the invention the condensed refrigerant present in the evaporator 12, as a result of the defrosting operation, flows through the restrictor 17 and is available to produce refrigeration in the lower temperature evaporator 13. Thus refrigeration is continued at the second evaporator, it being apparent that the thermodynamic efficiency of the system is high since the condensed refrigerant is immediately available to produce useful refrigeration in the evaporator 13.

Preferably, although not necessarily, the defrosting operation is terminated by opening of the contacts of switch 33, under the control of feeler bulb 25a, which latter is directly associated with the evaporator being defrosted. As will be apparent from the drawing, opening of the switch 33 de-energizes the solenoid associated with valve 21 and, consequently, refrigerant is again liquified in condenser 11 and flows through the restrictor 16 to be volatilized in evaporators 12 and 13. Should the switch 33 not terminate the defrosting operation, the valve 21 will be de-energized and closed, and the defrosting operation therefore terminated, upon right-hand movement of the main switch 29. As will be recognized by those skilled in the art to which the present invention pertains, a timer or other device can be utilized directly to return the main switch to the right-hand position, and thus re-establish the normal refrigeration cycle, without inclusion of control device 25 and switch 33. A number of alternative defrost control arrangements are now well known, and may be utilized in practice of this invention, but the foregoing description is sufficient for purposes of the present disclosure.

The apparatus has an additional important function which is the modulation or control of the refrigerating temperature of the compartment 14. Valve 22 and temperature-responsive switch device 24 perform this function in co-operation with the main switch 29. It will be noted that device 24 is also provided with a switch shown at 35, and further includes a control or feeler bulb 24a which is responsive to the temperature of the atmosphere within the compartment 14. Under conditions of normal refrigeration, when the main switch occupies the right-hand position shown in full lines, the valve 22 serves as a means for controlling the temperature of evaporator 12, and thence of compartment 14, by effecting controlled passage of refrigerant through the conduit 20 by-passing the second re-

strictror 17. When the temperature of the air within the compartment 14 reaches a predetermined upper limit switch 35 closes and the solenoid of valve 22 is placed across the line through the agency of the contacts of said switch 24, and through the right-hand blade of main switch 29 which latter is, of course, arranged in series circuit with the device 23 which serves to energize the compressor under normal conditions of operation. Energization of the solenoid associated with valve 22 opens that valve and, since restrictor 17 is by-passed, the pressure in evaporator 12 becomes equalized with the pressure in evaporator 13 and the temperature within said evaporator 12 is therefore reduced and approaches the temperature of the colder evaporator 13. When the temperature of compartment 14, as sensed by the feeler bulb 24a, is again reduced to a predetermined lower limit, switch 35 is opened by control device 24 and the solenoid associated with valve 22 is de-energized. Such de-energization results in closure of the valve 22 and re-insertion of the restrictor 17 into the circuit. The pressure in evaporator 12 accordingly rises, as does its temperature. Under all normal operation, however, including the defrosting cycle, the temperature of evaporator 13 remains substantially unchanged since the pressure within the latter evaporator does not vary materially and since all of the refrigerant supplied to the evaporator 12 flows to the evaporator 13 prior to return to the compressor.

It is to be understood that the specific switching devices and the paticular flow control means shown and described may be varied without departing from the broader aspect of the invention. For example, although normally closed valves are described, the switching circuit could be modified in such manner as to make it possible to substitute a normally open valve for the valve shown at 22, with a resultant saving of power. Additionally, modified flow of refrigerant, to supply gaseous refrigerant to evaporator 12, may be accomplished without the use of a valve. In any case, however, the restrictors 16 and 17 are rendered active, or the action thereof is modified, in accordance with the foregoing description and in such manner as to achieve the several functions of the system.

From the foregoing specification it will be evident that this invention provides novel and unusually efficient apparatus making it possible to utilize gaseous refrigerant to defrost one of a pair of series-connected evaporators, without interfering with normal operation of the other of said evaporators, and also to provide for ready and accurate control of the refrigerating temperature of both evaporators.

I claim:

1. In a series-flow refrigeration system, refrigerant circulating means, first and second series-connected evaporators, a pair of restrictors one of which is disposed between said circulating means and said first evaporator and the other

of which is disposed between said first and second evaporators, and apparatus providing, selectively, either for condensation of gaseous refrigerant within said first evaporator and consequent heating of the same with continuance of normal refrigeration within said second evaporator, or for modulation of the refrigerating temperature of said first evaporator, said apparatus comprising: a pair of conduits through which refrigerant may flow, one conduit being arranged to by-pass the restrictor which is disposed between said circulating means and said first evaporator, and the other conduit being arranged to by-pass the restrictor which is disposed between said first and second evaporators; and means including a first valve device adapted to control flow of refrigerant through said one conduit, said first valve device being effective, when opened, to cause gaseous refrigerant flowing from said circulating means to by-pass said first restrictor only and to flow into said first evaporator through said one conduit, whereby to effect condensation of gaseous refrigerant within said first evaporator, said means further including a second valve device adapted to control flow of refrigerant through said other conduit, said second valve device being responsive to predetermined temperature conditions at said first evaporator to move to open position and to cause flow of refrigerant through the said other conduit by-passing said second restrictor only, whereby to modulate the temperature of said first evaporator.

2. A refrigeration system in accordance with claim 1, and further characterized by the inclusion of a switching device adapted to control said second valve device to effect the recited modulation, said switching device including a temperature-sensitive element disposed in heat exchange relation with said first evaporator and being responsive to variations from predetermined temperature conditions at said first evaporator to control said second valve device and to initiate and terminate flow of refrigerant through the said other conduit.

3. A refrigeration system in accordance with claim 2, and further characterized by the inclusion of a second switching device having a temperature-sensitive element disposed in heat exchange relation with said first evaporator and being responsive to an elevated condensing temperature at said first evaporator to control said first valve device and to terminate flow of refrigerant through said one conduit.
